UNITED STATES PATENT OFFICE.

MARTIN A. DILLEY, OF WASEPI, MICHIGAN.

RAILWAY-CROSSING.

SPECIFICATION forming part of Letters Patent No. 337,253, dated March 2, 1886.

Application filed November 14, 1885. Serial No. 182,856. (No model.)

To all whom it may concern:

Be it known that I, MARTIN A. DILLEY, a citizen of the United States of America, residing at Wasepi, in the county of St. Joseph, 5 in the State of Michigan, have invented a new and useful Railway-Crossing, of which the following is a specification.

My invention has relation to improvements in railway-crossings of that class wherein two 10 lines of rails cross each other at about right angles. In crossings of this character it is necessary to provide ways at the points of intersection of the rails for the passage of the flanges of the wheels, the rails being broken 15 at these points, leaving openings wide enough to cause a heavy jar on the ends of the rails and foundation, and to have a damaging effect on the engine and cars. The ends of the rails become granulated and brittle, and 20 the damage to the cars is often immediate and apparent, and always certain in time. I seek to overcome these effects by interposing in the flange-space at the point of break in the rails a plug, which fills the space, and which 25 may be vertically reciprocated to set with the top of the rails or to drop below and leave the space open, the object being to provide a crossing having improved means whereby the traversed line of road shall for the time being 30 be made continuous; second, to provide means for operating the movable sections or parts of the crossing with certainty; and, third, to provide, in connection with the crossing, means for giving visual notification to the approaching 35 train of the condition of the crossing.

My invention therefore consists in the novel construction and combination of parts, as herein described, and as specifically pointed out in the claims made hereto, as required by the 40 statute.

I attain the objects of my invention by the mechanism illustrated in the accompanying drawings, wherein—

Figure 1 is a plan view of the crossing with 45 the shifting mechanism, a part of the latter being broken off. Fig. 2 is a side view of the complete apparatus. Fig. 3 is a longitudinal sectional view of the crossing. Fig. 4 is detached views of the plugs and mechanism in 50 detail, and Fig. 5 is a top plan view of the shifting or hand levers and connections.

In the drawings like parts are identified by like letters of reference.

The letter A designates the foundation-frame of the crossing. This consists of substantial 55 timbers laid at right angles and secured together to present a plane top face. Each angle of the frame is cut out to form seats a, for the plug-frames to rest in, as hereinafter described. These seats may be of any desired 60 shape. They may be round or rectangular, the object being to provide receptacles for the plug-frames, so that if sufficient space is made and access thereto had from the inner side of the foundation-frame to seat the plug-frames 65 and slides it will meet the purposes intended. I have shown the seats rectangular and the plug-frames corresponding in shape, and this form is preferred, since it affords better opportunity for arrangement of the mechanism of 70 the plugs.

The letters B designate the rails; the letters B' the fixed crossing, laid between the intersecting rails of the lines of road, and the letters B² designate the wing-rails of the 75 crossing. All of these are of ordinary construction, and laid and secured as usual. In the center pieces or plates, b, in the spaces between the terminals of the line-rails and the terminals of the line parts of the wing-rails, 80 are formed apertures b', through which the plugs are passed and in which they move.

The letters C designate the plug-frames, adapted to be disposed in the seats a of the frame. I have shown these plug-frames of 85 rectangular construction, and consisting of a bottom piece, c, to which are secured the side pieces, c', having the top c² firmly fixed thereon. This top piece, preferably, is extended to project over the side pieces and fasten on 90 the foundation-timbers of the frame. Forming a part of the top, or secured thereto, is a block, c³, of such thickness as to reach down on the slides of the plugs, and of such width as to leave a space on each side between the 95 sides of the frame, for the bell-crank levers to operate. Through the top piece and block are formed two vertically-arranged holes or ways, c⁴, in which are placed two plugs, c⁵ c⁶, the upper ends of which are arranged in the 100 apertures b' in the flange-spaces in the crossing. On each side of the block c³ is pivoted

a bell-crank lever, c^7 , one arm of which has a pivot projected through a slot, c^9 , in the block and into the stem of the plug, and the other arm, c^{10} , is detachably connected to the slide, so that as the slide is drawn to raise the plug the crank-lever will follow it by the connection to the plug, and when the slide is pushed back the lug on the side of the slide will run in the slot of the arm of the lever and push it back, thus assuring the positive movement of the plugs.

The letters c^{11} designate the slides which operate the plugs. These slides are horizontally arranged in the bottom of the plug-frames, and consist of a flat bar having fixed or formed thereon a step or plug-seat, c^{12} , made with an inclined forward end, c^{13} , whereby when the plug is seated on the forward portion of the bar and the slide is drawn to raise the plug it will ride up the incline and be easily lifted. To limit the forward movement of the slides, a stop-bar, c^{14} , is projected across the plug-frame over the forward portion of the slides, as shown, and the foot of the inclines abut against this bar.

The letters D designate cross-bars secured at the intersections of the timbers of the foundation, and having at their intersection a fixed pivot, upon which are journaled two disks, d^3 , d^4 , arranged one above the other; and to the outer part of these disks are attached one end of the rods d^5 , the other ends being attached to the slides under the plugs. To each disk is fixed a lever-arm, d^6 , d^7 , to which are connected the shifting-rods d^8 , d^9 , the other ends thereof being connected to the respective hand-levers. In the rods d^8 and d^9 are take-ups, substantially as shown, to adjust them, and permit contraction and expansion without detriment. At a suitable and convenient place, in any way secured, is a lever-frame, E, having pivoted therein hand-levers e^1 , e^2 , provided with sliding pawls or other proper means for holding them in a set position. Between the sides of the frame is mounted a bench, e^3 , upon which is pivoted a locking-plate, e^4 , which is kept in a normal position by a spring, e^5 , and returned to such position when turned to either side and released. This locking-plate is of such width that it will admit one of the hand-levers to slide between its edge and the inner face of the frame, but not both levers at the same time, and is so arranged that when one lever is thrown back the free end of the locking-plate is crowded over to the other side of the frame, and the end sets against the edge of the hand-lever, and locks it in that position against manipulation until the other hand-lever is thrown forward and the locking-plate is sprung from contact with the locked hand-lever. This arrangement prevents the watchman or tender from throwing both hand-levers at once, and also prevents him from throwing the normally-disposed hand-lever when the other is thrown back.

The letter F designates a signal-standard, to

the top of which is pivotally secured a signal-vane or semaphore. To each side of the pivot-support of the semaphore are secured rods f^1 , f^2 , having their lower ends fastened to a lever, f^3 , working on a pivot in a standard; and to this lever are suspended two rods, f^4 , f^5 , passed through guide-holes in the plate f^6 , fastened to the standard and arranged to project in a horizontal direction therefrom. Through guides on a properly-constructed table or foundation are the sliding bars f^7 , f^8 , having connecting-bars f^9 , f^{10} , running to the hand-levers. Each of these sliding bars has a hole, f^{11} , into which the ends of the rods suspended from the signal-lever project, respectively, and lock the slide, and consequently the hand-lever and apparatus, until the signal is turned and the rod is withdrawn from the slide. The signal-lever is set and held in any of the desired positions by means of a pin which is passed through a hole in the arm of the lever and into the frame on which the lever is attached, substantially as shown.

The operation is as follows: The normal position of the apparatus is with the hand-levers projected with their hand ends in the direction of the crossing. This leaves the top faces of the plugs in the spaces of the crossing below the top faces of the rails, and the spaces open in both directions, free for "wild-cat" or unannounced trains. Now, in case a train approaches the crossing from either the right or left hand in the arrangement of the plan shown in Fig. 1, then the hand-lever operating the plugs in the proper spaces is thrown back, operating the disk and drawing the slides under the plugs, raises them into the spaces, and makes the rail as even as though integrally continuous. As trains must await the signal at crossings of roads at grade, so here, and after drawing the hand-lever and forcing the plugs in position, the watchman or tender throws the signal-lever until the signal displays the proper notice for the train to proceed. After this train has passed over, the signal is returned to position and the lever thrown back to the normal position. To operate the other line or plugs is but a duplication of action, it being borne in mind that different signals are fixed upon to signal trains on the different tracks.

It will be noticed that when the plugs are lifted into position, and the signal disposed to indicate the fact, one of the bars of the signal-lever is projected through the hole in the sliding bar at the base of the signal-standard, as shown in Fig. 2, and locks the hand-lever in the thrown position until the signal is changed and the depending bar lifted up from its seat in the sliding bar. It will further be seen that the floor of the plug-frame is horizontal, and that the slides therein are laid directly on the floor and have direct contact with the ends of the plugs, and these, being fitted to the apertures through which they move, are sustained in vertical position thereby, their projecting parts being sustained in

the direction of the force by the vertical ends of the rails, and they have at all times a solid foundation.

The mechanism is positive in its action, and 5 so simple in construction that it cannot well fail to do just what it is purposed for. The plugs may be rounded; but it is evident that if made to fit the shape of the space between the rails they are the better.

10 I am aware that a railway-crossing has been made wherein vertically-arranged plugs are placed in the flange-spaces of the tracks and raised by a cam-lever mounted on a shaft, one end of said cam-lever engaging with a shoulder on the plug to raise and lower it, and the other end of the cam-lever operating to slide a plane-supporting block under and from under the plug.

What I claim as my invention, and desire 20 to secure by Letters Patent, is--

1. The combination, with a foundation of a railway-crossing and a fixed crossing arranged thereon, having apertures between the adjacent ends of the line-rails and the wing-rails, 25 of plugs movably disposed in said apertures, slides arranged under said plugs, formed with sections of different heights with an incline between them, and means, substantially as described, for reciprocating the slides, whereby 30 the plugs are raised and lowered, substantially as described.

2. The combination, with a foundation of a railway-crossing and a fixed crossing arranged thereon, of frames seated in the angles of the 35 crossing roads, plugs vertically arranged in ways formed in the frames and adapted to slide in the spaces between the crossing-rails, slides having sections of different heights with an incline between them, and means, 40 substantially as described, for reciprocating the slides, whereby the plugs are raised and lowered, substantially as specified.

3. The combination, with the foundation of a railway-crossing and a fixed crossing arranged 45 thereon, of frames seated under the angles of the crossing roads, plugs vertically arranged in ways formed in the frames and adapted to slide in the spaces between the crossing-rails, slides having sections of different heights 50 with an incline between them, means, sub-

stantially as described, for reciprocating the slides, and a bell-crank lever pivoted to the frame and having one arm connected to the plug and the other arm to the slide, whereby the plugs are raised and lowered, substantially 55 as described.

4. In combination, the foundation-frame having seats formed at the intersection of the timbers, the fixed crossing secured thereon, plug-frames arranged in the seats in the foundation, slides arranged horizontally in the frames and formed with a higher and a lower section or seats, plugs vertically disposed in ways in said frames and in the spaces between the line-rails and the wing-rails, a bell-crank 60 lever pivotally attached to the frames and having one arm connected to the plug and the other arm detachably connected to the slide, disks pivotally supported in the center of the crossing and having rods connected to the 65 slides, levers and rods connected to said disks, and hand-levers to rotate the disks, substantially as described, and for the purpose stated.

5. The combination, with a railway-crossing having vertically-moving plugs between 75 the spaces of the line-rails and the wing-rails, and mechanism for raising and lowering the plugs, of hand-levers connected to the shifting mechanism, and a locking-plate pivoted between the hand-levers and arranged to lock 80 the undrawn hand-lever in normal position when the other hand-lever is drawn back, substantially as described.

6. The combination, with the crossing mechanism, substantially as described, the hand-levers, the signal, and the signal-lever provided with depending rods, of the sliding bars at the base of the signal-standard, having perforations to receive the ends of the suspended bars, whereby the apparatus is locked in position when either set of plugs is lifted, substantially 85 as described, and for the purpose stated.

In witness whereof I have hereunto set my hand in the presence of two attesting witnesses. 95

MARTIN A. DILLEY.
